UNITED STATES PATENT OFFICE.

ARTHUR E. WHITE, OF CHICAGO, ILLINOIS.

CRIB AND BABY-CARRIAGE.

No. 802,249.

Specification of Letters Patent.

Patented Oct. 17, 1905.

Application filed December 28, 1904. Serial No. 238,680.

To all whom it may concern:

Be it known that I, ARTHUR E. WHITE, a citizen of the United States, residing at Chicago, in the county of Cook and State of Illinois, have invented certain new and useful Improvements in Cribs and Baby-Carriages, of which the following is a specification.

The objects of this invention are to furnish a support for the basket of a crib or baby-carriage which will allow of an easy swing for the basket and the occupant thereof; to construct a support for the basket of the crib or baby-carriage, which support consists of two companion frames, each having a bottom rail, a top rail, and a coil connection between the rails, the rails and coil being formed from the same rod or bar; to enable the basket to be adjusted in proper relation to the spring-coil as to accommodate the weight of the occupant and give a rising-and-falling movement which will be uniform and easy for the occupant of the basket; to so arrange the bottom rail, the top rail, and the connecting-coil as to furnish a continuous and uniform yield for the spring, by which any abrupt movement of the top rail will be prevented, and to improve generally the arrangement of the several elements entering into the construction of the crib and baby-carriage as a whole.

30 The invention consists in the features of construction and combinations of parts hereinafter described and claimed.

In the drawings, Figure 1 is a perspective view showing the support, comprising two companion frames and adjustable cross-rods, with the basket of the crib or carriage removed; Fig. 2, a side elevation of the support with the basket in position; Fig. 3, a front end elevation of the support with the basket removed; Fig. 4, a side elevation of the support arranged for use as a baby-carriage, and Fig. 5 a top or plan view with the basket removed of the construction shown in Fig. 4.

45 The support consists of two companion side frames A, each side frame having a bottom rail a , which at the forward end is coiled around to furnish a coil-spring a' , and continued from the coil-spring the rod is rearwardly extended, forming a top rail a'' , which has a yielding or rising-and-falling movement from the coil-spring and on which the basket of the crib or baby-carriage is supported. The coil-spring starts at a point, as a'' , and is turned to make one complete coil and a partial coil which departs from the circle of the

coil at a' , with an enlarged curvature which raises the plane of the top rail a'' higher than the top plane of the coil, thereby furnishing a uniform yield for the entire circle of the coil instead of a yield at one point only, thus giving a steady and easy rising-and-falling movement for the top rail.

The bottom rails a of the two companion side frames A are joined together at their rear ends by a cross rod or bar B, the ends of which enter an ear b on a socket b' , entered onto the end of each bottom rail and locked in position by a set-screw b^2 or otherwise, and as shown for the construction illustrated in Figs. 1, 2, 70 and 3 each ear b has journaled in its lower end a caster-wheel b^3 , furnishing a rolling support for the frame as a whole. The forward ends of the bottom rails a of the two side frames A are connected by a cross rod or bar C, the 75 ends of which enter ears c , each ear depending from a socket c' , entered onto the bottom rail and locked in position by a set-screw c^2 or otherwise, so that the forward connecting rod or bar C can be adjusted on the bottom rails, 80 so as to furnish a bearing for the yield of the coil-springs in a uniform and continuous manner. Each ear c has journaled in its lower end a caster-wheel c^3 , which completes the rolling support for the frame as a whole in 85 connection with the caster-wheels b^3 , thus enabling the crib to be readily rolled or moved from place to place.

The top rails a'' of the pair of side frames A are connected together at their rear ends by a 90 cross rod or bar D formed, as shown, on a curve. The ends of the cross rod or bar D are entered into bosses d , each boss on a socket d' adjustable on its top rail a'' and when adjusted locked in position by a set-screw d^2 or 95 otherwise. At the forward end of the top rails a'' is a cross rod or bar E, which, as shown, is on a curve. The ends of the cross-bar E are entered into bosses e , each boss on a socket e' adjustable on its top rail a'' and when adjusted locked and held in position by a set-screw e^2 or otherwise. The cross rods or bars D and E are curved in order to receive the ends of the basket F of the crib, and these rods or bars D and E are adjustable on the 100 side rails, so as to enable the point of counterbalance or equipoise for the springs to be changed to suit the weight of the occupant, and thereby maintain the proper relation between the crib and its point of support and 105 the coil-springs by which the rising-and-falling movement is governed and controlled by

the weight of the occupant. The adjusting of the cross rods or bars D and E rearwardly will give greater advantage of leverage from the weight of the occupant of the basket, and thereby give a uniform and easy rising-and-falling movement with a light-weight occupant, while the adjustment of the cross rods or bars D and E forwardly decreases the leverage transmitted by the top rails, which decrease of leverage, however, is overcome by the increase of weight for the occupant of the basket, so that the force exerted will overcome the resiliency of the coil-springs proportionately, and as a consequence the same amount of efficiency in an easy and uniform rising-and-falling movement is attained.

The rear end of each top rail α^2 has entered thereon a ball f , which gives a finished appearance and also guards against injury from striking or coming in contact with the ends of the top rails. The cross rods or bars for connecting the bottom rails of the two side frames furnish a rigid support for the bottom of the frame as a whole, and this support can be increased or decreased by adjusting the cross rods or bars away from or toward each other, so as to adjust the support correspondingly to the position of the basket, if necessary or desired, and the adjustable cross rods or bars D and E are curved or otherwise formed to allow the basket or body F to be entered between the top rails and the cross rods or bars in such position as to furnish a rest for the basket or body by which a counterbalance for the resiliency of the coil-springs is obtained by adjusting the end supports furnished by the rods or bars D and E as required for the weight of the occupant of the basket. The two companion side frames each having a bottom rail and a top rail with a coil connection between the two rails and the top rail by departing from the line of curvature of the coil raises or lifts the top rails for an incline from their rear end to the front end with the front ends clear of the coils, giving the coils a continuous yield between the bottom rail and the top rail for the entire circle of the coil, by which a uniform and easy rising-and-falling movement is attained without imparting any jar or quick drop and rise for the top rails, thus furnishing a rising-and-falling movement which will not jar the occupant of the crib.

The side frames A are capable of supporting a basket either for a crib or a baby-carriage without any material change in the side frames themselves and the connecting bars or cross-rods for the upper side rails. A construction of side frame adapted for use with a baby-carriage is shown in Figs. 4 and 5, in which the basket or body F is held in place between the top rails α^2 and end cross rods or bars D and E, as described for the construction of Figs. 1, 2, and 3. The ears b and c for the rear and front cross rods or bars B

and C instead of having the construction shown in Figs. 1, 2, and 3 are formed for the passage of axles g , each axle having on each end a carrying-wheel G of any suitable construction. Each bottom rail a is continued rearward, forming side rails h , which are bent upwardly and joined together by a cross-rail h' , the side rails h and cross-rail h' forming the handle H for the carriage.

The side frames A when used for a baby-carriage have the same yield as described for the side frames of a crib, and, like the crib, the basket for the baby-carriage can be adjusted rearward and forward, as required, for the weight of the occupant to furnish a counterbalance and counterpoise to the resiliency of the spring, by which the rising-and-falling movement is rendered uniform and easy, as described for the rising-and-falling movement of the crib.

What I claim as new, and desire to secure by Letters Patent, is—

1. The combination of two companion side frames each consisting of a bottom rail, a spring-coil and a top rail departing from the spring-coil with an upward incline toward its rear end, the two rails and the spring-coil being integral and formed from a single rod, cross-rods connecting the bottom rails at the front and rear ends, and adjustable cross-rods for the top rails, substantially as described.

2. The combination of two companion side frames, each consisting of a bottom rail, a spring-coil and a top rail departing from the spring-coil with an upward incline toward its rear end, the two rails and the spring-coil being integral and formed from a single rod, cross-rods connecting the bottom rails at the front and rear ends, adjustable cross-rods for the top rails, and a basket carried by the adjustable cross-rods of the top rails, substantially as described.

3. The combination of two companion side frames, each consisting of a bottom rail, a spring-coil and a top rail departing from the spring-coil with an upward incline toward its rear end, the two rails and the spring-coil being integral and formed from a single rod, a cross-rod connecting the rear ends of the bottom rails, a socket for each end of the cross-rod entered onto the bottom rail, locking means for the socket on its rail, a cross-rod connecting the forward ends of the bottom rails, a socket for each end of the cross-rod entered onto the bottom rail, locking means for the socket on its rail, a cross-rod connecting the rear ends of the top rails, an adjustable socket for each end of the cross-rod entered onto the top rail, locking means for the socket on its rail, a cross-rod connecting the front ends of the top rails, a socket for each end of the cross-rod entered onto the top rail, and locking means for the socket on its rail, substantially as described.

4. The combination of two companion side

frames, each consisting of a bottom rail, a spring-coil and a top rail departing from the spring-coil with an upward incline toward its rear end, the two rails and the spring-coil being integral and formed from a single rod, a cross-rod connecting the rear ends of the bottom rails, a socket for each end of the cross-rod entered onto the bottom rail, locking means for the socket on its rail, a cross-rod connecting the forward ends of the bottom rails, a socket for each end of the cross-rod entered onto the bottom rail, locking means for the socket on its rail, a cross-rod connecting the rear ends of the top rails, an adjustable socket for each end of the cross-rod entered onto the top rail, locking means for the socket on its rail, a cross-rod connecting the front ends of the top rails, a socket for each end of the cross-rod entered onto the top rail, locking means for the socket on its rail, and a basket carried by the adjustable cross-rod of the top rails, substantially as described.

5. The combination of two companion side frames, each consisting of a bottom rail, a spring-coil and a top rail departing from the spring-coil with an upward incline toward its rear end, the two rails and the spring-coil being integral and formed from a single rod, adjustable cross-rod for the bottom rails, and

adjustable cross-rod for the top rails, substantially as described. 30

6. The combination of two companion side frames, each consisting of a bottom rail, a spring-coil and a top rail departing from the spring-coil with an upward incline toward its rear end, the two rails and the spring-coil being integral and formed from a single rod, adjustable cross-rod for the bottom rails, adjustable cross-rod for the top rails, and a basket carried by the adjustable cross-rod of 35 the top rails, substantially as described. 40

7. The combination of two companion side frames, each consisting of a bottom rail, a spring-coil and a top rail departing from the spring-coil with an upward incline toward its rear end, the two rails and the spring-coil being integral and formed from a single rod, a front and rear socket for each bottom rail, an axle carried by the front and rear sockets of the bottom rail, a wheel for each end of 45 each axle, adjustable cross-rod for the top rails, and a basket carried by the adjustable cross-rod of the top rails, substantially as described. 50
